UNITED STATES PATENT OFFICE.

HENRY E. BANDLOW, OF CHICAGO, ILLINOIS.

DESIGN FOR A GASOLENE-HEATED SAD-IRON.

43,185.

Specification for Design.

Patented Oct. 29, 1912.

Application filed May 8, 1912. Serial No. 695,996. Term of patent 7 years.

To all whom it may concern:

Be it known that I, HENRY E. BANDLOW, a citizen of the United States, residing at Chicago, in the county of Cook and State of Illinois, have invented a new, original, and ornamental Design for a Gasolene-Heated Sad-Iron, of which the following is a specification, reference being had to the accompanying drawing, forming a part thereof.

The figure of the drawing is a perspective

view of a gasolene heated sad iron embodying my invention.

I claim—

The ornamental design for a gasolene heated sad iron, as shown.

HENRY E. BANDLOW.
